UNITED STATES PATENT OFFICE.

MICHAEL J. TRACY, OF ST. LOUIS, MISSOURI, ASSIGNOR TO PAULY JAIL BUILDING COMPANY, OF ST. LOUIS, MISSOURI, A CORPORATION OF MISSOURI.

INCLOSURE FOR SHOWER BATHS.

Application filed September 27, 1926. Serial No. 138,051.

My invention has relation to improvements in shower bath inclosures that are particularly adapted for erection in jails, or other institutions of similar character, and it consists in the novel features of construction more fully set forth in the specification and pointed out in the claims.

Briefly, the invention consists in a three-sided inclosure comprising two sections adapted to be superposed and snugly secured together by means of clips, thereby providing a knockdown construction that may be easily erected on the job.

The objects of the invention, aside from the knockdown feature, are the elimination of screws or bolts, and field riveting, at the same time obtaining the rigidity and strength of an integral construction. Other advantages inherent in the invention will be better apparent from a detailed description of the invention in connection with the accompanying drawings, in which—

Fig. 1 is vertical section taken through one wall of the inclosure on the line 1—1 of Fig. 2, the shower head being left in elevation and parts broken away; Fig. 2 is a horizontal cross-section taken through the inclosure on a plane indicated by the line 2—2 on Fig. 1; Fig. 3 is an enlarged sectional view of the left hand edge shown in Fig. 2; and Fig. 4 is a perspective view of the clips whereby the superposed sections are supported and held in intimate relation.

Referring to the drawings, W, W, W, represent steel partition walls, forming a part (in the present instance) of the jail construction, between which the shower inclosure A is disposed. The inclosure A is formed of two sheet steel plates 1 and 2 bent U-shaped so as to leave one side open. Each plate is supported from the walls W and spaced therefrom by a plurality of brackets 3 and clips 4.

The brackets 3 are riveted or welded to the walls W and the clips are fastened in like manner to the plates 1 and 2, and in erecting the plates 1 and 2 in place the lower plate 1 is first mounted by means of its clips 4 on the two lower rows of brackets 3. In order that there may be no leakage of water to adjacent parts of the building, a lead drip pan 5 is positioned beneath the plate 1, its upper edge extending between the walls W and the lower part of plate 1. The edges 6, 6 of plate 1 are bent outwardly as

shown (Fig. 3) and have their extremities 7, 7 turned back so as to fit snugly into spaces S, S, formed between side walls W, W, and marginal angles 8, 8 which are fastened to said walls in spaced relation by means of narrow strips 9, 9 (Fig. 3). The angles 8, 8 provide the necessary backing for the edges 6, 6 of plate 1. After plate 1 is in place, the inclosed space between said plate and walls W is filled with concrete C, said concrete embedding the pan 5 around which it forms a base 10, and above said pan a floor 11.

After plate 1 has been securely fixed in place, plate 2 is mounted by means of its clips 4' on the three upper rows of brackets 3' on the walls W, W, W. The bottom row of clips 4' on plate 2 are spaced sufficiently above the lower edge 2' of plate 2 so that when the clips of this row engage the brackets positioned to receive them, the edge 2' of plate 2 will overlap the upper edge 1' of plate 1 and contact closely therewith. Having positioned plate 2, the space S formed between said plate and walls W is also filled with concrete C so that the entire space between the shower inclosure A and walls W is provided with a concrete filling. A metal coping 12 is secured to the upper edge of plate 2 and the inner surface of walls W, spanning the space between said plate and walls, and giving to the inclosure a proper finish. A shower head 13 is secured to one side of plate 2 near the top thereof, said inclosure being connected with a water-pipe 14, the supply of water being controlled from a valve (not shown) located in some readily accessible position, said valve being under the control of the jailer or guard in the case of prisons.

Having described my invention, I claim:

1. In combination with a plurality of partition walls, a shower bath inclosure spaced from said walls, said inclosure comprising a plurality of U-shaped plates in superposed relation, means for mounting the plates on the inner surfaces of the walls, said mounting means consisting of brackets projecting from the walls and clips secured to the sides of the plates, the brackets being adapted for engagement between the clips and plate and a suitable filling material in the space between the plates and partition walls.

2. In combination with a plurality of partition walls, a shower bath inclosure, or stall, spaced from said walls, the sides of

said inclosure comprising plates supported by the partition walls, said supporting means comprising upstanding brackets fixed to the walls and depending clips fixed to the plates, said brackets and clips being shaped for intimate engagement and a suitable filling material in the space between the plates and partition walls.

3. In combination with a plurality of partition walls, a shower bath inclosure, or stall, spaced from said walls, the sides of said inclosure comprising plates supported by the partition walls, said supporting means comprising upstanding brackets fixed to the walls and depending clips fixed to the plates, said brackets and clips being shaped for intimate engagement, and a concrete filling in the space between the plates and partition walls.
- 10 4. In combination with a plurality of partition walls, a shower bath inclosure, or stall, spaced from said walls, the sides of said inclosure comprising plates supported by the partition walls, said supporting means com-

prising upstanding brackets fixed to the walls and depending clips fixed to the plates, said brackets and clips being shaped for intimate engagement, and, angles vertically secured in spaced relation to the side partition walls and disposed to define the margins of the inclosure, the edges of the plates having lateral extensions abutting said angles and nesting in the spaces between the angles and the side walls and a suitable filling material in the space between the plates and partition walls.

5. In combination with a plurality of partition walls, a shower bath inclosure spaced from said walls, the sides of said inclosure comprising plates supported by the partition walls, the supporting means thereof comprising cooperating formations on the walls and plates adapted for frictional engagement, and a suitable filling material between the walls and plates.

In testimony whereof I hereunto affix my signature.

MICHAEL J. TRACY.
